Des. 229,806

Patented Jan. 8, 1974

229,806

SKI RACK OR SIMILAR ARTICLE

Walter L. Hasser, 3 Loma Linda Drive,
Colorado Springs, Colo. 80906

Filed Nov. 22, 1971, Ser. No. 201,263

Term of patent 14 years

Int. Cl. D6—06

U.S. Cl. D6—125

FIG. 1 is a front elevational view of a ski rack or similar article showing my new design;

FIG. 2 is a top plan view thereof;

FIG. 3 is a side elevational view thereof; and

FIG. 4 is a bottom plan view thereof.

The broken line representation of skis and ski poles in FIG. 1 is for purposes of illustration only.

I claim:

The design for a ski rack or similar article, as shown and described.
